UNITED STATES PATENT OFFICE.

GIUSEPPO CAROCCIO, OF NEW YORK, N. Y., ASSIGNOR, BY MESNE ASSIGNMENTS, TO WELTE-MIGNON CORPORATION, OF NEW YORK, N. Y., A CORPORATION OF DELAWARE.

FALL-BOARD OPERATING MECHANISM.

Application filed July 13, 1923. Serial No. 651,358.

This invention relates to fall boards for musical instruments and operating mechanism therefor, being adapted particularly for use in grand pianos.

5 The primary object of my invention is the provision of an improved operating mechanism for moving a fall board into and out of covering position by a humanly operated device in position to be operated from the 10 outside of the case.

Another object of my invention is the provision of a structure wherein a rock shaft and lever construction is connected at its operating end to a fall board and at its operated end to a humanly operated means whereby the fall board may be moved to covering position.

Referring to the drawing wherein I have illustrated a preferred embodiment of my 20 invention,

Figure 1 is a vertical cross section of my invention as applied to a grand piano.

Figure 2 is a view similar to Figure 1 but with the fall board in its rearward 25 position.

Figure 3 is a plan view of my invention, portions of the piano being omitted for the sake of clearness.

Figure 4 is a plan view of the bottom of 30 the instrument showing the operating mechanism as viewed from below.

9 designates the keybed of a grand piano, 10, a key and 11 the upper casing. The fall board to which I have shown my invention applied is a type which reciprocates on 35 guide rails, to and from its covering position over the keys.

12 designates the fall board which is supported on a suitable supporting or guiding 40 rail 13 at each end thereof, the rails being secured to the sides of the piano casing. The fall board 12 is provided with suitable 45 runners 14 of leather or felt or any suitable material for contacting with the upper surfaces of the rails 13.

At the forward end of the fall board is a pivoted portion 16 which by lifting on the forward edge, may be folded about the hinge 17, into the cut away portion 18. The fall 50 board is free to be lifted about its rear end as a center to permit clearance of the keys 10 during the folding operation. In practice, suitable securing means will preferably be provided to prevent the dropping of the

hinged portion 16 when folded in the 55 space 18.

Adjacent the bottom of the keybed, I have provided bearings 19 in which is mounted a lever in the form of a rock shaft 20 having two arms 21 extending upwardly for operating the fall board and an arm 22 extending downwardly to operate the shaft as will be described. The arms 21 are arranged parallel and are of the same length. The keybed is cut away sufficiently to permit the 65 proper operation of the lever arms 21.

Small blocks 23 are secured to the rear of the fall board 12. Pivotedly connected to the blocks 23 and the arms 21 are the links 24 which are identical in length and shape. 70

Mounted in suitable bearings 25 for axial movement therein is a rod 26 having at its end, nearest the front of the instrument, a suitable knob or handle 27. A link 28 connects the rod 26 and the lever arm 22 to 75 operate the latter from the former.

The operation of my invention is as follows:—

Assuming that the fall board is in closed or outer position as shown in Figure 1, the 80 forward end of the board is lifted and the lower leaf folded in the space 18. The fall board 12 is now permitted to return to its position as shown in Figure 1. It may now be pushed inwardly by pressing on the 85 forward edge. If desired, not to press on the fall board, the handle 27 may be pulled outwardly, exerting a tension in the link 28 causing a turning of the shaft 20 in a clockwise direction as viewed in Figure 1, placing the link 24 under tension and thus pulling the fall board to the rear.

When it is desired to bring the fall board to its outer or closed position, it is only necessary to push inwardly on the handle 95 27. This places the link 28 under compression, causes the shaft 20, with the arms 21, to turn in a counterclockwise direction as viewed in Figure 1. This causes the links 24 to be placed under compression, thus 100 forcing the fall board 12 to be moved to its outward position. The forward end may then be lifted and the hinged portion swung downwardly. The fall board is then lowered in place.

105 While I have shown and described a modification of my invention, I desire to have it understood that I do not limit myself to the

exact showing and that modifications and changes may be made without departing from the spirit of my invention and within the scope of the appended claims.

5 Having described my invention, what I claim is:

1. A musical instrument casing provided with a key bed and with an opening in its front portion and above the key bed, and 10 also having a fall board arranged over the key bed and spaced therefrom, and slidable within said opening, in combination with an operating member below the key bed, and connections extending through the key 15 bed and operative by said member to slide the fall board forward from its inner to its outer position.
2. A musical instrument casing provided with an opening in its front portion and 20 with a fall board movable slidably forward and rearward within said opening, the fall board having a depression in the underside of its forward portion and provided in advance of said depression with a hinged member 25 which is foldable upward and lies in said depression when in its folded position, in combination with a lever mechanism arranged within the casing and connected to the fall board, and an operating member 30 connected to said lever mechanism and operative therethrough to slide the fall board forward from its inner to its outer position.
3. A musical instrument casing provided with an opening in its front portion and 35 with a fall board movable slidably forward and rearward within said opening and with its upper surface spaced from the lower wall of the opening, the fall board having a depression in the underside of its forward 40 portion and provided in advance of said de-

pression with a hinged member which is foldable upward and lies in said depression when in its folded position, in combination with a lever mechanism arranged within the casing and hingedly connected to the rearward portion of the fall board, and an operating member connected to said lever mechanism and operative therethrough to slide the fall board forward from its inner to its outer position. 45

4. A musical instrument comprising keys, a fall board mounted to have reciprocatory movement over the keys, a shaft, an arm extending from the shaft, a connection between the arm and the fall board, and an operating member connected to the shaft and operative therethrough to impart sliding movement to the fall board. 50

5. A musical instrument comprising keys, a fall board, means for guiding the fall board forward and rearward over the keys, a shaft, a plurality of arms extending from the shaft, link members connecting the arms with the fall board, an additional arm extending from the shaft, a humanly operable rod mounted to reciprocate and a link connecting the rod with the last named arm. 55

6. A musical instrument comprising a key bed and keys, a fall board mounted to have reciprocatory movement over the keys, a shaft, a plurality of arms extending from the shaft, connections between said arms and the fall board, and a reciprocatorily mounted operating member arranged below the bed and having connection with said shaft to 70 operate the same to impart sliding movement to the fall board. 75

In testimony whereof I affix my signature.

GIUSEPPO CAROCCIO.
